UNITED STATES PATENT OFFICE.

GEORGE W. SAGE, JR., OF PORT CHESTER, NEW YORK.

BICYCLE.

Application filed October 26, 1920. Serial No. 419,583.

To all whom it may concern:

Be it known that I, GEORGE W. SAGE, Jr., a citizen of the United States, residing at Port Chester, in the county of Westchester 5 and State of New York, have invented certain new and useful Improvements in Bicycles; and I do hereby declare the following to be a full, clear, and exact description of the invention, such as will enable others 10 skilled in the art to which it appertains to make and use the same.

This invention relates to improvements in bicycles, and more particularly to the front or steering forks thereof and connections 15 thereto.

The object in view is the absorbing and cushioning of shocks delivered through the front wheel and its connections to those portions of the body of the rider sustained 20 thereby.

A further object in view is the provision of such cushioning means with a minimum variation from accepted types of commercial forks.

With these and further objects in view as will in part hereinafter become apparent and in part be stated, the invention comprises certain novel constructions, combinations and arrangements of parts as subsequently specified and claimed.

In the accompanying drawings,—

Figure 1 is a view in side elevation of the front portion of a bicycle, parts being broken away.

Figure 2 is an enlarged, detail, fragmentary view, partly in elevation and partly in section, of a fork embodying the features of the present invention.

Figure 3 is a side elevation thereof, the lower portions of the fork and a fragment of the lower portion of the mud-guard being seen, and parts being shown in section.

Figure 4 is a transverse, vertical section taken on the planes indicated by line 4—4 of Figure 2, and looking upward.

Figure 5 is a vertical section taken on the planes indicated by line 5—5 of Figure 2, and looking in the direction indicated by the arrows, parts being shown in elevation.

Figure 6 is a view similar to Figure 5 of a slightly modified embodiment of the invention.

Figure 7 is a horizontal section through the lower portions of the arms of the fork and through the mud-guard and its connection, parts being seen in plan.

Figure 8 is an enlarged, detail view, partly in elevation and partly in vertical section on the plane indicated by line 8—8 of Figure 7.

Referring to the drawings by numerals, 1 indicates the frame of a bicycle having the usual head 2 through which extends the usual stem or steering post 3 of the front forks, which latter consist of a pair of arms between which is journaled the front wheel 4 of the bicycle. Each of said arms is identical with the other and the description of the details of one is equally applicable to the other. The fork is made up of 60 the said arms connected by a transverse head 5 from which the stem 3 upstands, the transverse head 5 being of the usual commercial type consisting, in the particular embodiment illustrated in the drawings, of 65 spaced transversely-arranged plates. Each arm of the fork consists of a tubular section 6 fixed to one end of the transverse head 5 and telescoping with respect to a section 7 of tubing which extends down to and carries the axle 8 of the wheel 4. The tubing of the sections 6 and 7, as clearly seen in Figure 4, is transversely oval and longitudinally tapered, tapering downward from the transverse head 5 to the lower point of 70 the respective arm of the fork. Because of the longitudinal taper, the telescoping portions of the sections 6 and 7 would become loose fitting as they move toward a 75 nested or more completely telescoped condition, which for convenience will be called inward, if provision were not made to prevent such a result, and relative movement in the opposite direction of sections 6 and 7, 80 which will be hereinafter called outward, 85 would effect closer fitting or tightening of the sections if not provided against. To enable the sections to freely reciprocate or move in and out with respect to each other without varying the relative fit between the 90 two sections, the section 6 is provided with 95 plates 9, 9 filling the terminal portions of the ellipse described by a cross section through section 6, each plate 9 presenting a flat face toward the edges of section 6, 100 and the said edges of the section 6 are provided with plates 10, 10 for presenting flat faces toward and in engagement with the 105 flat faces of the plates 9. Plates 9 and 10 taper longitudinally, that is become thinner, 110 in the direction in which the particular section 6 or 7 becomes narrower incident

to its taper, so that the distance between the flat faces of the two plates 10 is the same at one end of the plates as it is at the other and this is also true of the distance between 5 the flat faces of the plates 9, so that the plates 9 and 10 provide a closely fitting guide for allowing free reciprocation of the sections 6 and 7 while preventing rattling or loosening of the parts. To prevent complete 10 separation of the sections, a transverse pin 11 is provided, extending through section 7 and being anchored to section 6. The pin 11 preferably assumes the form of a simple rivet and the walls of section 7 are 15 slotted at 12 to accommodate the pin 11, and at the same time permit longitudinal movement of section 7 with respect to section 6. For maintaining the section 7 at its lowermost point normally and for cushioning 20 the telescoping action of the sections, a spring 13 is arranged in the section 6. The spring 13 is preferably transversely shaped to conform to the interior shape of section 6 and has its upper end resting 25 against a portion of the transverse head 5 with its lower end resting against the upper end of section 7, so that section 7 is stressed downward under spring tension at all times. The section 6 may be secured to the trans- 30 verse head 5 in any of various well known ways, as, for example, by being passed through the lower plate of the head and abutted against the upper plate thereof, and then brazed to the two plates.

35 The structure thus arranged insures a resilient connection between the wheel 4 and the frame of the bicycle, so that in passing over rough roads or obstacles, the give of the springs 13 is added to the cushioning effect of the tire of wheel 4 in affording a resilient support for the hands of the operator and for so much of the weight of his body as may be delivered through his hands.

45 Since the axle of wheel 4 is thus capable of assuming variable distances from the head 2, it is apparent that connections for the lower portion of a mud guard for wheel 4 may not be had with lower portions of 50 the fork unless provision be made to compensate for such variations. To this end, the mud guard 14, which is connected to the transverse head 5 in the usual manner and extends downwardly about the wheel 4, has 55 its lower portion connected by rods 15 pivoted at their forward ends to the lower portions of the arms of the fork. The detail construction of the pivotal connection of the rods 15 is best seen in Figures 7 and 8, 60 wherein the section 7 is shown as having one of its walls apertured and provided internally with a nut 16 into which is threaded the cap screw 17 having the shouldered or journal portion 18 about which extends the 65 portions of the eye 19 formed at the for-

ward end of the respective rod 15. The rear ends of the rods 15 are connected by being penetrated by a bolt 20, which extends through the crown 21 of the guard 14. The bolt 20 is provided with appropriate nuts 70 at its ends for securing the rods 15 and between the ends of the rods 15 the bolt 20 is surrounded by sleeve sections 22, 22 and 23. The crown 21 of mud-guard 14 is offset from the main portion of the mud-guard, 75 providing shoulders through which the bolt 20 extends, and the several sleeve sections 22 and 23 are arranged to abut against the said shoulders and provide spacers so as to keep the rods 15 properly spaced apart. To 80 avoid tendency on the part of the rod 20 to move longitudinally, it is preferable to provide a rivet 24 which extends through the sleeve section 23 and a portion of the rod 20. Since the sleeve section cannot 85 move longitudinally because of its endwise engagement with the shoulders of crown 21, the rod 20 is effectively held against longitudinal shifting incident to possible loosening of the nuts on the rod. 90

In Figure 6 I have shown a slightly modified embodiment of the invention in which the same reference numerals are applied to identical parts and the same description will apply, the modification consisting 95 essentially in arranging the section 6' to telescope with sections 7' in a manner to prevent loosening by expanding the walls of both sections at those portions which would be ordinarily reduced by virtue of 100 the longitudinal taper. The arms of the fork having the sections 6' and 7' are tapered the same as that above described, save for the telescoping portions of said sections, which telescoping portions are shaped by 105 expansion to conform in size and contour to each other so as to provide an effective guide as clearly seen in Figure 6. The sections are, of course, tubular and of transversely elliptical form. 110

It should be obvious that as the mud-guard 14 is rigidly anchored at its upper portion to the transverse head 5, the movement of the rods 15 incident to telescopic action of sections 7 will effect a movement of the lower portion of the guard 14, but such movement will be slight and will be in the nature of a spring action on the part of the guard 14 as a whole. 115

What is claimed is:—

1. In a bicycle fork, the combination with a transverse head and a steering post upstanding therefrom, of fork arms extending downwardly from the head and each comprising telescoping sections of longitudinally tapering form, means for cushioning the movement of one of the sections relative to the other, and means for limiting the extent of telescoping movement of the sections, the telescoping portions of the sec- 125 130

tions being shaped and proportioned with respect to each other for preventing lateral or edgewise play.

2. In a bicycle fork, the combination with 5 a transverse head and a steering post up- standing therefrom, of fork arms extending downwardly from the head and each comprising downwardly tapering telescoping sections of transversely elliptical form, 10 and means for cushioning the movement of one of the sections relative to the other.

3. In a bicycle fork, the combination with a transverse head and a steering post up- standing therefrom, of fork arms extending 15 downwardly from the head and each com- prising telescoping sections of trans- versely elliptical form tapering downwardly throughout their length, and means for cushioning the movement of one of the sec- 20 tions relative to the other, the sections being shaped and proportioned relative to each other such as to prevent edgewise or lateral play.

4. In a bicycle fork, the combination with 25 a transverse head and a steering post up- standing therefrom, of fork arms extending downwardly from the head and each comprising downwardly tapering telescoping sections of transversely elliptical form, 30 and means for cushioning the movement of one of the sections relative to the other, and plates fixed to the respective sections and proportioned to compensate for variations incident to the taper and elliptic form of the 35 sections by providing engaging portions of

the plates proportioned to prevent relative movement of the sections otherwise than in a telescoping direction.

5. In a bicycle fork, the combination with a transverse head and a steering post up- 40 standing therefrom, of fork arms pendent from the head and each comprising trans- versely elliptical telescoping sections, and a helical spring, substantially elliptical trans- versely, disposed within the upper section 45 of each arm and arranged between the lower section of the respective arm and a portion of the transverse head for exerting cushioned resistance to relative telescopic action of the sections. 50

6. In a bicycle structure, the combina- 55 tion of a front fork formed with arms com- prising cushioned telescoping sections, a mud guard attached to the fork and extend- ing partway about a front wheel and hav- ing an offset crown providing outstanding shoulders, a bolt extending through the shoulders of the crown of the guard and beyond the edges of the guard, rods pivoted to the arms and to the extended end por- 60 tions of the bolt, and spacing sleeves mounted on the bolt between the shoulders of the crown and the engaging ends of the rods.

In testimony whereof I affix my signature in presence of two witnesses.
